UNITED STATES PATENT OFFICE.

MICHAEL JOSEF GRAEF, OF ST. LOUIS, MISSOURI.

STAMP-AFFIXING DEVICE.

1,117,488.

Specification of Letters Patent. Patented Nov. 17, 1914.

Application filed March 23, 1912. Serial No. 685,764.

To all whom it may concern:

Be it known that I, MICHAEL JOSEF GRAEF, a citizen of the United States, residing at St. Louis, in the State of Missouri, have invented new and useful Improvements in Stamp-Affixing Devices, of which the following is a specification.

This invention pertains to stamp affixing devices and aims to provide such a device that will positively affix a stamp to an envelop or the like through the instrumentality of the elements embodied herein and that will be hereinafter fully described and pointed out in the appended claims.

An object of this invention is to provide a device of the foregoing nature which consists of a few operating parts thereby reducing to a great extent the loss of energy due to friction.

Another object of this invention is to provide a stamp affixing device wherein all the operating parts are disposed in such a manner that access may be readily had to them for the purpose of their removal and attachment of new parts whenever occasion requires.

With the foregoing and other objects in view my invention consists in such details of construction and in the arrangement and combination of parts as will be hereinafter more fully described and specifically pointed out in the appended claims.

In describing my invention in detail reference will be had to the accompanying drawings wherein like characters denote like or corresponding parts throughout the several views, and in which:

Figure 1 is a plan view of my improved stamp affixing device, Fig. 2 is a bottom view of the same, Fig. 3 is a side elevation, Fig. 4 is a cross sectional view of the device taken on line 4—4 of Fig. 2, Fig. 5 is a sectional view taken on line 5—5 of Fig. 3, Fig. 6 is a sectional view taken on line 6—6 of Fig. 3, Fig. 7 is a sectional view taken on line 7—7 of Fig. 6, Fig. 8 is a cross sectional view taken on line 8—8 of Fig. 7, Fig. 9 is a perspective view of a detail portion of my device, Fig. 10 is another detail view.

In the accompanying drawings which fully illustrate the preferred form of my invention, the numeral 1 designates the body portion thereof which is provided at its ends with the cross pieces 2. The body portion of my invention is preferably formed from metal. However, I desire it to be under-

stood that any other suitable substance may be substituted without departing from the spirit of the invention in the least.

The under side of the body portion has projecting thereinto a sheet member 3 which serves a purpose that will be hereinafter more fully specified. One edge of the member 3 is slightly upturned as shown at 4 thereby obviating any difficulty in moving the device over an envelop to its position.

The cross pieces 5 are journaled through the body portion and adapted to receive rubber rolls 6 through which are adapted to be fed stamps in the manner set forth herein-after. For the purpose of moistening the underside of the stamps as they are fed over the rolls 6, a perforated tube 7 is provided which carries therein a sponge member 8. Water may be admitted to the sponge member for the purpose of keeping the same moistened through one end of the tube 7 which is left open. It is now readily obvious that the roll 6 and the tube 7 are disposed flush with the surface of a platform 9 which extends across the body portion and has connection with the member 3. The stamps are adapted to be held upon the platform and by so disposing the rolls and perforated tube they may be more readily fed onto the envelop as will hereafter appear.

The cross pieces 5 and the roll 7 are provided at one end with gear wheels 10 which mesh with the rack bar 11, the said rack bar being slidably mounted within a substantially tubular shaped element 12 which is supported upon the body portion as shown at 13. A slot 14 is provided in the upper portion of the element 12 through which extends a handle 15 which is fast to the rack bar through the medium of an arm 16 and has journaled therethrough a rod 17 as shown at 18. The rod above mentioned has coiled thereabout a spring 19 which is adapted to return the handle to position after it has been operated. A portion 20 of the handle projects through a second slot 21 in the element 12 for a purpose that will presently appear. It is now readily obvious that when the handle 15 is operated either manually or mechanically that the rack bar will be so moved as to rotate the rollers and the tube. When stamps are held upon the platform and this operation occurs one of them will be automatically fed onto an envelop (not shown). After pressure is released from the handle it will

be returned into its former position through the medium of the coil spring 19.

Secured to the rack bar at one end as shown at 22 and having its other end operative through the element 12 is a rod 23. This rod is spaced from the rack bar a distance nearly the length of the body portion of the device whereupon it is abruptly bent downwardly as shown at 24 and secured to the bar. A curled end 25 of a cross arm 26 operates upon the rod for a purpose herein-after appearing. The body portion is provided with a slot 27 through which extends one end of the cross arm 26. The end of the cross arm which extends through the slot is, as above pointed out, mounted upon the rod 23. The other end of the cross arm is journaled in the body portion at a point considerably below the horizontal plane wherein 10 operates its other end. Secured to the cross arm 26 and preferably intermediate its ends is a plug 28 which carries at its under side a plate 29. The underside of the plate may be provided with strips of blotting material 15 or the like for obvious purposes. It will now be appreciated that when the handle is operated in the manner set forth above, and the curled portion 25 of the cross arm 26 contacts with the bent portion 24 of the rod 23, that the plate 29 will be lowered considerably. When this operation occurs and when a stamp has been fed over the rolls and tube and is moved beneath the plate, it 20 will be positively applied to the element 25 therebeneath.

It has proved advantageous to provide a means for securing a plurality of stamps upon the platform 9 and with this in view a hollow member 30 is provided within the body portion and provided with apertures 31 at its sides. A plate 32 is provided which carries an extension 33 which extends through the apertures 31 in the member 30. For the purpose of holding the plate in place, a leaf spring 34 is provided upon its upper side and is disposed as illustrated. The attachment of the plate and the removal thereof is greatly facilitated by the provision of an eyelet 35.

50 In the operation of my invention, the stamps are first disposed within the device beneath the plate 32, the latter of course holding the same forcibly upon the platform, the lower of the stamps being in engagement with one of the rolls 6. The device is then held in the hand of the operator and placed upon the envelop at a predetermined point, after which the knob 15 is pushed forwardly. The manipulation of 55 the knob 15 will cause actuation of the rack bar 11 which in turn causes the member 25 to travel upon the rod 23. This operation will of course depress the rod and impart a subsequent movement to the pressure plate 29. By this time the rolls 6 and

moistening element 7 have been rotated, whereby the lower of the stamps will be fed directly beneath the pressure plate, and consequently forcibly affixed upon the envelop. The glued side of the same, being downward, contacts with the moistening element 7, consequently it is moistened before being disposed beneath the pressure plate.

It is thought from the foregoing that the advantages and novel features of my device 75 will be readily appreciated.

I desire it to be understood that I may make slight changes in the construction and in the arrangement and combination of parts provided such changes fall within the 80 scope of the subjoined claims.

Having thus fully described my invention, what I claim as new and desire to secure by Letters Patent, is:—

1. In a device of the character described, 85 a body portion provided with a platform for holding a plurality of stamps, a moistening roll carried by said body portion and disposed flush with the surface of said platform, feed rolls carried by said body portion for feeding stamps over said moistening roll, a plate carried within said body portion and adjacent one of said feed rolls adapted to be depressed when said rolls are rotated for the purpose described.

2. In a device of the character described, 90 a body portion, a platform provided in said body portion for holding a quantity of stamps, a moistening roll carried by said body portion and flush with the surface of 95 said platform, feed rolls adjacent said moistening roll and adapted to feed said stamps beneath a plate which is carried within said body portion, gear wheels upon said rolls, means for rotating said gear wheels, said means adapted to operate said plate for the purpose described.

3. In a device of the character described, 100 a body portion having its upper side open, a platform therein for supporting a quantity 105 of stamps, a moistening roll positioned within said body portion and flush with the surface of said platform, a pressure plate mounted within said body portion feed rolls 110 disposed upon each side of said moistening roll adapted to feed said stamps beneath said plate carried within said body portion, gear wheels carried by said rolls, a substantially tubular shaped element carried by one side of said body portion, a rack bar operating within said element and adapted to mesh with said gear wheels, a handle connected to said rack bar, whereby it may be moved so as to rotate said rolls, thereby feeding said stamps beneath said plate, and means carried upon said rack bar whereby said plate may be depressed for the purpose 115 described.

4. In a device of the character described, 120 a body portion provided with a stamp hold-

- ing platform, a moistening roll provided within said body portion and flush with the surface of said platform, feed rolls disposed upon each side of said moistening roll, gear 5 wheels carried by said rolls, a substantially tubular member carried by one side of said body portion and having a rack bar operative therein, said rack bar adapted to mesh with the said gear wheels, a handle projecting through the upper and lower sides of said substantially tubular shaped member, a rod secured upon said rack bar a cross arm having one end journaled in said body portion, the other end connected to said rod, a 10 plate supported by said cross arm and means whereby when said handle is operated, said plate will be depressed for the purpose described.
5. In a device of the character described, 15 a body portion provided with a stamp holding platform, a moistening roll carried by said body portion and flush with the surface of said platform, feed rolls disposed upon each side of said moistening rolls, gear 20 wheels carried by said rolls, a substantially tubular shaped element carried by said body portion, a rack bar meshing with said gear 25 wheels and operating within said element, a handle carried by said rack bar and adapted to project through the upper and lower sides of said element, a rod journaled through said element, a coil spring surrounding said rod, a portion of said handle operating upon said rod and engaging said 30 coil spring, a rod having one end secured to said rack bar and the other end operative through said element, said body portion provided at one side with a slot through which is adapted to extend one end of a cross arm, 35 one end of said cross arm adapted to operate upon said second mentioned rod, the other end of said cross arm adapted to be journaled in said body portion, a plate supported by said cross arm, said handle adapted 40 to be operated against the tension of said 45 coil spring whereby said rolls may be operated by said rack bar and said plate depressed for the purpose described.
6. A stamp affixer including a body having a portion thereof formed to provide a 50 platform for holding the stamps, means for holding the stamps from displacement on said platform, means for moistening and conveying the stamps to a predetermined point, and a plate for affixing the stamps to objects 55 automatically upon their arrival at said predetermined points.
7. A device of the character described including a body portion having a supporting portion integrally formed therein, a detachable securing plate carried within said body portion above said supporting portion for holding stamps on said supporting portion, feed and moistening rollers journaled in said body for moistening and feeding the 60 stamps to a predetermined point, and a reciprocating pressure plate actuatable in said body with the operation of said rollers, for applying the stamps to objects placed beneath said plate. 65
8. In a device of the character described, a body portion including a supporting part to hold stamps thereon, a detachable securing plate mounted above said supporting part for retaining the stamps from displacement, feed rolls to convey the stamps to a predetermined point, a moistening element mounted between said feed rolls whereby the stamps are moistened while being conveyed, a reciprocating pressure plate for affixing the 70 stamps to an object upon their arrival at said predetermined point, and means for actuating said feed rolls, said moistening element, and said pressure plate, substantially as described. 75
